UNITED STATES PATENT OFFICE.

WILLIAM T. MILLIGAN, OF BOSTON, MASSACHUSETTS, ASSIGNOR, BY MESNE ASSIGNMENTS, TO THE OCEAN STEAMSHIP BERTH COMPANY, OF PORTLAND, MAINE.

SELF-LEVELING SHIP'S BERTH.

SPECIFICATION forming part of Letters Patent No. 376,542, dated January 17, 1888.

Application filed April 11, 1887. Serial No. 234,326. (No model.)

To all whom it may concern:

Be it known that I, WILLIAM T. MILLIGAN, of Boston, in the county of Suffolk and State of Massachusetts, have invented a new and useful Improvement in Self-Leveling Ships' Berths, of which the following is a specification.

My improvement relates to the construction of the hanging mechanism at the head and foot of the berth; and it consists in mechanism whereby the movement of the berth about its longitudinal axis is rendered easy and steady with the least amount of friction and wear, and also in mechanism whereby such motion is prevented altogether, so as to enable the berth to be locked either temporarily or permanently, as desired.

In the drawings, Figure 1 is a longitudinal section showing the mode of hanging the berth at the head and foot. Figs. 2 and 3 are elevations of the ends of the berth, partly broken away to show the construction of the hanging mechanism. Either form may be used for the head or foot of the berth; or the hanging mechanism may be alike at both head and foot, if thought best. Figs. 7 and 8 show modes of keeping a berth upon its bearings. Figs. 4, 5, and 6 show details of the locking mechanism, and will be specifically referred to below.

The berth now to be described is one the longitudinal axis of which always remains at a fixed distance from the side wall of the state-room or any other fixed object.

A is the piece which forms the head or foot of the berth. It is circular, and is provided with circular lip or bearing a.

A' A' are the sides of the berth, which may be so constructed as to allow the berth to swing on a cross-axis, if thought best.

B is a casting consisting, mainly, of a circular track, b, of, say, two inches less diameter outside than the inner diameter of the lip a. This casting also provides bearings, to which the various levers connected with the locking mechanism may be pivoted, thus taking all the strain off the state-room bulk-head and providing a bearing for these pivots which is very strong, although taking up but little extra room.

C is a carriage provided with wheels c, axled thereto. These wheels are of proper diameter and properly placed to keep the longitudinal

axis of the berth coincident with the center of the circular track. The lip a of the head bears upon them, and they rest upon the circular track and serve to materially reduce the friction between the head and track. This carriage also has rollers c', which are in diameter about the width of the track, and hence serve to brace the berth between the two bulk-heads and steady its movement. The carriage may be circular in form, as indicated in Fig. 2, or a portion of its lower part may be cut away and the place of the part omitted taken by a wire or cord, c² c², and a weighted segment, c³, which shall serve to keep the carriage on top of the track.

As shown in Fig. 3, the weight c⁴ is attached to one corner of a thin triangular piece of casting, and two wires, c², each attached to one end of the carriage, are attached to the other corners of the triangular segment. The segment is also provided with a wheel, which is sometimes convenient in steadying the berth, though not necessary. This segment c³ is sufficiently thin to lie between the lip a, which is slightly cut away for the purpose, and the casting below the track, and below the lip it is made thick enough to allow the weight c⁴ to be attached thereto either by a screw or in some other suitable way. The segment-piece is best provided with one or more wheels, c, as shown, and also should have rollers c' to do away with any lateral friction.

The upper part of the periphery of the circular piece or head A is provided with teeth extending about two-thirds around the head, one half of these teeth being shaped, as shown, to engage with the pawl D, and the other half to engage with the pawl D'. These pawls are pivoted to the casting at d, and are held to the teeth by suitable springs. They are provided with angle-arms and rods or wires d' d', whereby they may be controlled from the yoke-lever d². By means of this yoke-lever d², the bell-crank d³, and the rods d⁴ the pawls are connected to the lever-handle E, by means of which the parts can be operated and the berth locked or unlocked at pleasure. The teeth, being located upon the top of the head, are out of the way, and no movement given to the berth to raise it can disengage the pawls and head. Moreover, the pawls, when so placed, keep the

berth upon the bearings while locked. When placed below, if one end of the berth be accidentally lifted off the pawls, the pawls will be drawn in by their springs, so as to interlock 5 with a lower pair of teeth than was contemplated, and hence, when the force tending to raise the berth is removed, the berth will not return to its former position and be supported upon the track or other support provided for the purpose, but upon the pawls.

The handle E is a lever fulcrumed at e upon a plate, e', attached to the side wall of the state-room, the handle being so placed that when it is vertical (see Figs. 1 and 4) the berth will be 15 locked, the pawls being engaged with the teeth in the periphery of the head, and when it is thrown over to one side, as indicated in Fig. 5, the pawls will be disengaged, and the handle, being then latched by the latch F, will prevent 20 the re-engagement of the pawls until the latch has been thrown, in the manner to be explained.

The handle locking and latching mechanism is as follows: The locking mechanism consists 25 of a tongue, g, which slides in a box, g', and is held up by springs g². (See Fig. 6, which shows this mechanism in section.) This tongue is located right over a cavity, e², in the handle E, so that when it is forced down it will engage with the cavity and prevent any movement of the handle. The movement of the tongue may be controlled by a Yale or other lock, (indicated at G,) the bolt g³ of which throws the tongue and confines it in the cavity of the handle until the lock-bolt is withdrawn by 35 turning the key. By means of this locking mechanism the berth may be permanently locked and used as if it were a stationary berth.

40 The latching mechanism is for temporary use, as when the passenger is getting in or out of the berth. It consists of a latching-lever, F, which is pivoted at h to the plate J, and rocks back and forth between the tongue-box 45 g' and the back side of the plate J, which conceals the mechanism. (See Fig. 6.) The latching is performed by a shoulder, h², which, when the handle E is turned to one side so as to withdraw the pawls and allow the berth to 50 swing, engages with it and prevents it from returning until released by the releasing mechanism, being held against it by the spring h³.

The releasing mechanism consists of a lever, K, fulcrumed at k, which interlocks with and 55 bears against the latching-lever F at k', its further end being linked to the releasing-pull k², which can be moved up and down in the slot j in the plate J. When it is desired to release the handle and cause the pawls to engage with 60 the head, the releasing-pull k² is pulled down, thereby raising the bearing-point k' of the lever K F and moving the shoulder h² out of the way, so that the springs connected with the pawls may be allowed to act and cause the 65 pawls to engage the teeth in the head of the berth, at the same time drawing the handle to

a vertical position. It is obvious that such a latching-lever may be moved in a variety of ways, either by a releasing-pull connected directly with it or by some other system of links and leversthan that shown; but the mode shown has proved very satisfactory in use.

The latch-lever spring is a convenient means for keeping the latch engaged; but it is evident that some other controlling device may be adopted—for example, the mechanism which moves the latch may itself be locked in any one of a number of known ways of locking handles.

It is necessary in such a berth as is above described to axle the supporting-wheels to a common connection. Loose friction-rollers used to hold the berth upon the highest part of a circular track would invariably work down under the berth, and hence would become useless for the purpose of holding up the berth. Being journaled to the carriage instead of to either the track or the head, the axles of these rollers are not strained, as they would be if the rollers did not have a motion independent of either the head or the track.

The advantage of using a circular carriage either made of a circular casting, as shown in Fig. 2, or a segmental casting with a bottom-weighted piece, as shown in Fig. 3, is that, if any force tending to raise the berth off its bearings is applied to the berth while in motion, it will be prevented from moving the berth out of center, the rollers underneath it keeping it from being raised, and hence the carriage will always be in the proper position for doing its work without the restriction of any springs, which always cause more or less friction. Moreover, if springs be used in a berth where the supporting-wheels are all of the same size to limit the motion of a segmental carriage, there is always the danger that if the berth be listed in any way while the ship is rolling the carriage will be sprung back to its position on top of the track while the berth is still at an angle with the floor of the state-room, and when the berth falls upon the track again the upper middle portion of its bearing-surface will not rest upon the middle wheel of the carriage, but upon one of the side wheels, so that when it rotates again the springs will sustain an unequal strain and the berth will not move easily or with regularity.

Instead of having one or more rollers or wheels between the track and the bearing-surface underneath the berth to keep the berth down, it is evident that in a berth having a circular head supported upon wheels one or more friction-rollers, l, secured to studs in the bulk-head above the head (see Fig. 7) and bearing slightly on its outer edge, or a piece, m, about three inches wide projecting from the lower part of the head, extending around about one-third of the circumference of the head, and provided with a curved slot, m', struck from the center of the head and fitting over a friction-wheel, m², attached to the bulk-head, (see

Fig. 8,) will enable the berth to rotate and at the same time keep it upon its carriage; but in either of these cases the motion of the carriage must be limited in some way where the wheels are of the same diameter to keep it upon the upper part of the track.

What I claim as my invention is—

1. In a self-leveling ship's berth, the combination of the berth having at each end a circular bearing-surface, two circular tracks, each located upon a suitable support in close proximity to one of said bearing-surfaces, and two carriages of substantially the kind described, provided with supporting-wheels all of the same diameter, each carriage resting upon its track and upholding one of said bearing-surfaces, as and for the purposes set forth.

2. In a self-leveling ship's berth, the combination of the berth having at each end a circular bearing-surface, two circular tracks, each located upon a bulk-head or other support in close proximity to said bearing-surface, and two carriages of substantially the kind described, provided with supporting-wheels all of the same diameter, each resting upon its track and upholding with its wheels one of said bearing-surfaces, and means, substantially as above described, whereby when said berth is in use neither end of it can be lifted off its supporting-wheels, all substantially as and for the purposes set forth.

3. In a self-leveling ship's berth, in combination with a track, the self-righting carriage above described, consisting of a number of wheels axled to a common curved connection, the ends of said common connection each being provided with a wire projecting therefrom, a weight joining said wires midway between the ends of said carriage, whereby said carriage is normally kept centered on the top of said track, all as set forth.

4. A self-leveling ship's berth adapted to rotate about its longitudinal axis, having at each end a circular bearing-surface, two circular tracks, each located upon a bulk-head in close proximity to said bearing-surface, and two carriages of substantially the kind described, each located upon its track and supporting one of said bearing-surfaces, the outer upper periphery of said bearing-surfaces being provided with teeth, in combination with pawls located above said bearing-surface and adapted to interlock therewith, and means, substantially as described, whereby said pawls shall be operated, all as set forth. 45

5. In combination with the berth-locking mechanism of a self-leveling ship's berth, the handle E, having a cavity, as described, a spring-restrained tongue, g, and a lock, G, located above said tongue, as and for the purposes set forth. 50

6. In a self-leveling berth, in combination with the berth-locking mechanism and its operating-handle E, the handle-latching mechanism above described, consisting of the latch-lever F and mechanism, substantially as described, whereby it may be moved, all as set forth. 65

7. In a self-leveling ship's berth, in combination with the handle E and the berth-locking mechanism, the latch-lever F, spring h³, releasing-lever K, and means, substantially as described, whereby said releasing-lever may be operated, as set forth. 70

In testimony whereof I have hereunto subscribed my name this 6th day of April, A. D. 1887.
